US00D981956S

(12) **United States Design Patent** (10) **Patent No.:** **US D981,956 S**
(45) **Date of Patent:** **** Mar. 28, 2023**

(54) **CHARGING CASE FOR WIRELESS
EARPHONES**

(71) Applicant: **GUANGDONG XIZHONGXI
TECHNOLOGY CO., LTD.,**
Dongguan (CN)

(72) Inventor: **Xiuhong Deng**, Shaoyang (CN)

(73) Assignee: **GUANGDONG XIZHONGXI
TECHNOLOGY CO., LTD.,**
Dongguan (CN)

(**) Term: **15 Years**

(21) Appl. No.: **29/795,708**

(22) Filed: **Jun. 21, 2021**

(51) LOC (14) Cl. **13-02**

(52) U.S. Cl.

USPC **D13/108**

(57) **CLAIM**

The ornamental design for a charging case for wireless earphones, as shown and described.

DESCRIPTION

FIG. 1 is a perspective view of a charging case for wireless earphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the charging case for wireless earphones where the charging case for wireless earphones is in a closed state.

The broken lines in the drawings depict portions of the charging case for wireless earphones that form no part of the claimed design.
